UNITED STATES PATENT OFFICE.

WILLIAM H. BACHTEL, OF CANTON, OHIO.

TROLLEY.

SPECIFICATION forming part of Letters Patent No. 726,211, dated April 21, 1903.

Application filed March 10, 1903. Serial No. 147,062. (No model.)

To all whom it may concern:

Be it known that I, WILLIAM H. BACHTEL, a citizen of the United States, residing at Canton, in the county of Stark and State of Ohio, have invented certain new and useful Improvements in Trolleys; and I do hereby declare that the following is a full, clear, and exact description of the same, reference being had to the annexed drawing, making a part of this specification, and to the letters of reference marked thereon.

The present invention has relation to overhead trolleys; and the object thereof is to provide means whereby the trolley will be prevented from accidentally disengaging itself from the wire and will be more effective than the trolleys ordinarily in use and also possess the strength, durability, and effectiveness required in this class of device; and it consists in a trolley constructed substantially as shown in the drawing and hereinafter described and claimed.

In the drawing, which represents a perspective view of a trolley embodying my invention, A designates a portion of the roof of a car, to which is suitably connected a tubular standard B, in which is telescopically or adjustably secured the trolley-pole C, the pole being held in its adjustable position by means of set-screws *a* or other means found most preferable in holding the pole stationary in the tubular standard. The pole C has a laterally-extending arm *b* and an arm *c*, which carries a suitable roller D, said roller being connected to said arm by a hanger *d* of any preferred construction. The arms *b* and *c* are connected together by a spring E of any suitable construction, and said spring is secured to the arms in any desirable manner found best adapted to the purpose, thereby giving the arm *c* a yielding action to adapt it to the trolley-wire F, and the adjustability of the pole C enabling it to be lengthened or shortened to adjust it to the height of the trolley-wire. The arm *c* is substantially parallel with the trolley-wire, and the roller D connected to the end of the arm will be directly over and on line with the pole C, thereby giving effectiveness to the trolley, insuring the roller to remain in engagement with the trolley-wire when passing around a curve or over a switch, and the arm *c* being

parallel with the trolley-wire enables the roller to run on the wire in either direction without changing the position of the trolley. 55

A wire G of suitable thickness and length and of the desired strength and preferably of copper has a coil *f* at or near its center, which coil extends over an upright post *e*, projecting from the tubular standard B. 60 That portion of the wire above and below the coiled spring forms arms which are suitably connected to the trolley-pole and the tubular standard, respectively, as shown at *g*, *h*. In the present instance I have shown 65 the wire coiled around trolley-pole and standard and afterward brazed or otherwise suitably fastened; but other means may be resorted to in fastening the ends of the wire in place of the coils, as I do not wish to limit 70 myself to any particular means of accomplishing this object, and many changes or modifications may be resorted to without in any manner affecting the essential features of the invention, and any form of standard 75 and any means may be employed for adjustably connecting the trolley-pole thereto and holding it in its adjusted position without departing from the principle of the invention. 80

A suitable coupling H is provided for connecting the cross-wire I to the wire F, said coupling consisting of the radial arms *i*, which are originally flat and afterward bent around the wires, as shown. 85

Any suitable coupling may be employed for connecting together the wires as found best adapted to the purpose, but that shown is considered the most simple and practical for the purpose intended. The wire G forms 90 a coupling for the trolley-pole and the tubular standard and is preferably of copper and forms a conductor for the electric current should connection fail between the pole and standard. 95

Should it be necessary to extend the trolley-pole to an increased length, the coil in the wire G will admit of this extension, the coils being separated in accordance with the raising of the pole and compressed when the pole is lowered. 100

Having now fully described my invention, what I claim as new, and desire to secure by Letters Patent, is—

1. In a trolley, a suitable standard, a pole adjustably connected thereto, an arm and a roller connecting therewith to engage the trolley-wire, and a suitable spring connecting the arm with the pole, substantially as and for the purpose set forth.
2. In a trolley, a trolley - pole having a laterally - extending arm, an arm substantially parallel with the trolley-wire, a suitable roller connecting with said arm, and a suitable spring connecting the two arms together, substantially as and for the purpose described.
3. In a trolley, a tubular standard, a trol-

ley-pole adjustably connected thereto, a suitable post projecting from the standard, a wire having a plurality of coils engaging the post and the ends of the wire suitably connected to the trolley-pole and standard respectively, substantially as and for the purpose specified.

In testimony whereof I affix my signature in presence of two witnesses.

WILLIAM H. BACHTEL.
